RESILIENT CAR WHEEL

Russell J. Wittmer, Cleveland Heights, Ohio, assignor to National Malleable and Steel Castings Company, Cleveland, Ohio, a corporation of Ohio

Application July 31, 1933, Serial No. 682,936

14 Claims. (Cl. 295—11)

This invention relates to wheels for street cars or other railway vehicles. The invention more particularly provides a novel wheel comprising a rim relatively movable with respect to a hub and resilient means between the rim and hub for effectively cushioning the movements therebetween. An object of the invention is the provision of a novel construction whereby there is produced a resilient wheel of marked efficiency while at the same time obtaining the advantages of simplicity of construction and economy of manufacture and assembly. The invention comprises in this connection provisions for cushioning movements between the rim and hub through the interposition of rubber means in a particularly efficient manner and without the necessity of vulcanizing the rubber or providing special clamping means therefor. A further feature of the invention resides in novel provisions for protecting the rubber against the heat developed by the brakes. Other features and advantages will be more particularly pointed out in the ensuing description and set forth in the claims appended hereto.

In the accompanying drawings:

Fig. 1 is a view in side elevation of a wheel embodying my invention.

Fig. 2 is a vertical sectional view on an enlarged scale, taken on line 2—2 of Fig. 1.

Fig. 3 is a vertical sectional view on line 3—3 of Fig. 2, with parts broken away.

Fig. 4 is a vertical sectional view on line 4—4 of Fig. 2, with parts broken away.

Fig. 5 is a detail view of one of the rubber inserts.

Referring to the drawings, the wheel of my invention comprises a metal rim 2 having the usual wheel contour. A metallic hub member is shown at 3 having a radially extending flange 4 parallel to the radially extending web or flange 5 of the rim 2. The latter is provided with a circumferential shouldered portion 6 for the reception of a metal disk 7. Bolts 8 extend thru said disk 7, flange 4, and web 5, as well as thru a vertical flange 9 of a brake drum 10 and serve to maintain the parts in assembled relation.

Projecting from the web 5 toward the flange 4 are studs 11; while similar studs 12 extend from disk 7 toward said flange. The latter is provided on opposite sides with studs 13. As shown the studs 13 on the face of the flange 4 adjacent the web 5 extend into overlapping relation to the studs 11; i. e., a single vertical plane perpendicular to the axis of the hub may be passed thru said studs 11 and 13. Likewise the studs 13 on the opposite side of flange 4 project a sufficient

distance toward disk 7 to bring said studs into overlapping relation to the studs 12 on said disk. In Fig. 3 the studs 13 (appearing in front elevation) are shown positioned in a plurality of circumferential series; each stud 11 in a series being positioned between a pair of studs 13. If desired, however, the studs 11 and 13, instead of alternating in each circumferential series, could be arranged in separate series; i. e., the series closest to hub 3 could consist entirely of studs 13, the next circumferential series could be composed entirely of studs 11, and so on. Furthermore, the studs instead of being arranged in radial lines as shown, could be staggered so that one or more would not be in radial alignment with adjacent studs. The arrangement of studs 12 with respect to the studs 13 on the face of flange 4 adjacent to disk 7 may be similar to that above described between studs 11 and the studs 13 nearest web 5. In Fig. 4 the studs 13 extending toward disk 7 are shown in section and the studs 12 in front elevation.

Between the web 5 and flange 4 there is positioned a rubber disk or sheet 14 having holes 15 (Fig. 5) for receiving the respective studs 11 and 13. A similar rubber disk 14 is positioned between flange 4 and disk 7. The holes in said rubber disk are no larger in diameter than the studs which they receive, whereby a snug fit is obtained. It is to be noted that the bolts 8 are also snugly engaged in openings in the rubber disks 14 and thus cooperate with said disks in the same manner as the studs 11 and 12. The openings 16 in the flange 4, however, thru which said bolts extend, are larger than the bolts, thus providing for relative movement between the hub and rim. Clearance is provided, as indicated at 17, between each stud and the member opposite.

The purpose of this clearance is two-fold, the first being to permit relative movement between the hub and rim, as will be noted further hereinafter, and the second to prevent abrasion of the rubber where it contacts with the inner surfaces of disc 7 and web 5 and the opposite sides of flange 4. If the studs 11, 12 and 13 extended to the above surfaces the adjacent rubber would be moved by the studs and the outer and inner surfaces of the rubber caused to slip along the surfaces of the adjacent metallic members, thus causing abrasion. By making the studs shorter than the thickness of the rubber sheet the end of a stud will press into the rubber on relative

movement of the parts without disturbing the contact between the rubber and the adjacent metal surfaces. A radius or chamfer may be provided on the ends of the studs to further increase 5 the effect of the clearance.

It will be observed that the construction here disclosed enables relative movement to take place between the wheel rim and hub in any direction. Thus, the hub can move in a plane at right 10 angles to its axis until the clearance indicated at 18 is taken up; while said hub can move parallel to its axis in either direction until clearances 17 are taken up. Referring to Fig. 3, it will be seen that, assuming upward movement of the hub 3 15 with respect to the rim 2, the rubber between the studs designated 11' and 13' will be in compression and that surrounding the pair of studs 13' and 11' under tension. In other words, in movement between said hub and rim in a given direction, certain portions of the rubber will be in compression and simultaneously other portions will be under tension. The same is true of downward movement of the hub with respect to the rim, as well as of torsional movements therebetween. 20 25 The aforesaid action of the rubber is obtained without any vulcanizing of the rubber to the adjacent metal surfaces, and without any clamping of the rubber between the flange 4 and the web 5 or between said flange 4 and the disk 7. There is no necessity for initial compression of the rubber between said flange 4 and the members 5 and 7. However, if desired, the thickness of the rubber sheets may be increased so that initial compression thereof is obtained upon tightening 30 35 bolts 8 to a desired extent. Moreover, very little additional machining of parts is required over that necessary for the ordinary type of rigid wheel.

The brake drum 10 enables the braking action to occur at a distance from the rim 2 and materially decreases the heat transmitted to the rubber. While the drum might be cast integral with the disk 7, it is preferred that it be constructed as a separate part. Said drum, as shown, 40 45 includes an upper flange cut away at portions 19 (Fig. 4), providing a series of circumferentially spaced lugs 20 engageable with the disk 7. Also said drum has a lower circumferential series of lugs 21 separated by spaces 22 and engageable 50 with said disk. Thru the upper and lower series of lugs 20, 21, aforesaid, the main body portion of said drum 10 is spaced from the disk 7 and a circumferential air chamber 23 is provided therebetween, and in addition the spacing of the lugs 55 in each series provides further for engagement of the drum with the disk 7 at spaced points. Substantial diminution of heat transfer is thus further effected. Moreover, during rotation of the wheel air circulates through the openings 22 60 and 19 and cavity 23, thereby cooling the wheel and drum and this is facilitated by the flanges 24, which, in addition to reinforcing the drum, provide additional air circulation by their fan action while the wheel is rotating. Additional restriction 65 in the transfer of heat from parts of the wheel that become heated during operation may be had by placing asbestos or similar material adjacent the rubber sheets and between contacting surfaces of the metal.

70 As shown in Figs. 3 and 4, the studs in the series nearest the axis of the hub 3 may be of less cross sectional area than those at greater distances from said axis; the cross sectional area of the studs of the respective series being shown as 75 increasing with the distance of the studs from

said axis. The holes in the rubber disks are correspondingly of areas increasing with the radial distance from the axis of the disk, as shown in Fig. 5. The characteristics of the wheel can be modified by punching holes at points intermediate the holes 15 in the rubber disks. This also would permit a certain amount of flow of rubber as the bolts are tightened up in case the surfaces of the castings are such as to have irregular projections which would press the rubber inwardly 10 during tightening of the bolts.

It will be seen that the structure above described can be readily disassembled without removal of the hub member from the journal. When it is desired to change the rim, the nuts of 15 the bolts 8 may be removed and the rim slipped off without disturbing any of the other parts.

While obviously the web or flange 5 of the rim member 2 need not be cast integral therewith but may instead, if desired, be made separate therefrom and secured thereto (for example, in a manner similar to disk 7), it suffices for an understanding of my invention that it be illustrated as integral with said rim and it has accordingly been 20 25 so shown.

The terms and expressions which have been employed are used as terms of description and not of limitation and there is no intention, in the use of such terms and expressions, of excluding any equivalents of the features shown and described, 30 or portions thereof, but it is recognized that various modifications are possible within the scope of the invention claimed.

I claim:

1. A resilient car wheel comprising a hub having a flange projecting therefrom, a rim having a radial web spaced from said flange, projections extending from said flange toward said web, projections extending from said web toward said flange and in overlapping relation to the projections of said flange, and rubber means between said flange and said web and extending around a projection on said web and thence to and around a projection on said flange with consequent tensioning of portions of said rubber means in response to movement of one of said projections away from the other.

2. A resilient car wheel comprising a hub having a flange projecting radially therefrom, a rim having a radial web spaced from said flange, a disk of rubber between said flange and said web and having openings therein, projections from said web fitting into certain of said openings, and projections from said flange fitting into others of said openings, the projections from said web and flange respectively extending axially of the wheel into overlapping relation to each other.

3. A resilient car wheel comprising a hub having a flange projecting radially therefrom, a rim having a radial web spaced from said flange, projections extending from said web toward said flange, projections extending from said flange toward said web, said projections being so arranged that a plane transverse to the axis of the hub and passing through said projections on said flange also passes through said projections on said web, and a rubber element having openings into which the respective projections of said web and flange extend, and adapted to be placed concurrently under compression and tension in different portions thereof in response to relative movement between said flange and web.

4. A resilient car wheel comprising a hub having a flange extending radially therefrom, a rim having a radial web spaced from said flange, a

- rubber element between said flange and said web, and means comprising projections on said web and flange extending into axially overlapping relation and fitting into holes in said element for holding the latter in position and placing different portions of said element concurrently under compression and tension respectively during relative radial movement between said web and said flange.
5. A resilient car wheel comprising a hub having a flange extending radially therefrom, a rim having a radial web spaced from said flange, rubber means between said flange and said web, and means comprising axially overlapping projections for concurrently placing certain parts of said rubber means under compression and other parts under tension during radial movement of said rim in a given direction with respect to said hub.
10. 6. A resilient car wheel comprising a hub, a rim, rubber means between said rim and said hub, and means comprising axially overlapping projections for concurrently placing certain parts of said rubber means under compression and other parts under tension, during movement of said rim in a given direction radially of said hub.
15. 7. A resilient car wheel comprising a hub member, a rim member, an element extending radially from one of said members, other elements extending radially from the other of said members on opposite sides of the first mentioned element, rubber means interposed between said first mentioned element and said other elements, projections extending from opposite sides of the first mentioned element into said rubber means, projections from said other elements extending into portions of said rubber means, said projections and said rubber means being so constructed and arranged that portions of said rubber means are placed under tension and other portions are concurrently placed under compression during relative movement in a given direction between said hub and rim members, and bolts extending through all of said elements and said rubber means, with provisions enabling one of said members to move with respect to said bolts.
20. 8. A resilient car wheel comprising a hub member, a rim member, rubber means between said rim and said hub, an element extending radially from one of said members, other elements extending radially from the other of said members on opposite sides of the first mentioned element, projections from the first mentioned element extending into said rubber means, and projections from said other elements extending axially into overlapping relation to the first mentioned projections and also extending into portions of said rubber means between the first mentioned projections.
25. 9. A resilient car wheel comprising a hub having a flange extending radially therefrom, a rim having a web, a plurality of series of studs extending around said flange at different radial
- distances from the axis of said hub, a plurality of series of studs extending around said web at different radial distances from the axis of said hub, and rubber means between said web and said flange and receiving said studs, said projections being so arranged that a plane transverse to the axis of the hub and passing through said projections on the flange also passes through said projections on said web.
10. A resilient car wheel comprising a hub having a flange extending radially therefrom, a rim having a web, a circular series of studs on said flange, a circular series of studs on said web, said studs on said web being interposed between said studs on said flange and overlapping the same, and rubber means between said web and said flange and receiving said studs.
15. 11. A resilient car wheel comprising a hub having a flange extending radially therefrom, a rim having a web, a plurality of series of studs on said web and flange, the cross sectional areas of the studs increasing with increase of radial distance from the axis of said hub, and rubber means between said flange and said web and having holes receiving said studs, the studs on said web overlapping the studs on said flange with consequent tensioning of portions of said rubber means in response to relative movement between said hub and rim.
20. 12. A resilient car wheel comprising a hub having a flange extending radially therefrom, a rim having a web, a plurality of circular series of studs on said flange, a plurality of circular series of studs on said web, the studs of each of said series on said web being interspersed among the studs of a corresponding series on said flange, the cross sectional areas of the studs increasing with the radial distance thereof from the axis of said hub, and rubber means between said flange and said web having holes for receiving said studs, the studs on said web overlapping the studs on said flange with consequent tensioning of portions of said rubber means in response to relative movement between said hub and rim.
25. 13. A car wheel comprising a hub having a flange extending radially therefrom, a rim having a web, rubber means between said web and said flange, and means comprising studs on said flange and web for concurrently placing portions of said rubber means under compression and other portions under tension in movement of said hub with respect to said rim in any of a plurality of directions.
30. 14. A car wheel comprising a hub having a flange extending radially therefrom, a rim having a web, rubber means between said web and said flange, and means comprising studs on said flange and web for concurrently placing portions of said rubber means under compression and other portions under tension upon rotation of said rim with respect to said hub in any of a plurality of directions.

RUSSELL J. WITTMER.
